UNITED STATES PATENT OFFICE.

CLIFTON BURT CORELL, OF NEW YORK, N. Y., ASSIGNOR TO GRAFF, WASHBOURNE & DUNN, OF NEW YORK, N. Y., A CORPORATION OF NEW YORK.

COMPUTING MACHINE.

Application filed August 12, 1921. Serial No. 491,678.

To all whom it may concern:

Be it known that I, CLIFTON BURT CORELL, of the city of New York, borough of Manhattan, in the State of New York, have invented certain new and useful Improvements in Computing Machines, of which the following is a specification.

This invention relates particularly to an adding machine in which a series of computing mechanisms of successive denominations are associated and have connecting carrying devices. These mechanisms, as shown, are of the chain type and are organized to be operated singly in performing a computation, as by inserting a stylus successively in links of the chains at the points denoting successive digits of a number to be added and at each insertion drawing the stylus to the end of the run. The object of this invention is to provide a computing mechanism of this general type of substantial construction and in compact form and properly safeguarded against erroneous computation.

In the accompanying two sheets of drawings which form a part of this specification:

Figure 1 is a plan broken away of a machine which embodies this invention.

Fig. 2 is a longitudinal vertical section of the machine on the line II—II of Fig. 1.

Fig. 3 is a transverse vertical section through the computing wheels on the line III—III of Figs. 1, 2 and 4.

Fig. 4 is a vertical section through the shaft which carries the computing wheels on the line IV—IV of Fig. 3. Fig. 5 is a transverse vertical section through the machine showing the end movement arresting detents on the line V—V of Figs. 1 and 2.

Fig. 6 is a vertical section through the resetting wheels on the line VI—VI of Fig. 8.

Fig. 7 is a transverse vertical section through the resetting wheels on the line VII—VII of Figs. 1, 2 and 8.

Fig. 8 is a vertical section through the resetting mechanism on the line VIII—VIII of Fig. 7.

Fig. 9 is a perspective view of two links of the chains.

The adding machine comprises a series of computing mechanisms of successive denominations each consisting of a pair of wheels of which one is a computing wheel 10 and the other is a reset wheel 11. Both wheels are formed with sprocket teeth and are con-

nected by an endless chain 12. A table 13 underlies the upper runs of the chains and carries digits which show through the links of the chains to guide the operator in inserting the stylus for operating. Each computing mechanism except the one to the extreme left is a lower computing mechanism with respect to the one immediately to the left and is connected through its computing wheel by a pawl 14 pivoted to the side thereof with the computing wheel of the next higher computing mechanism and is the carrying device between the two mechanisms. The computing wheels are formed with sprocket teeth 15, 15 on the tips of which are numbers which register the results of the computation. The teeth pass through the links of the chain and flanges 16, 16 at the bases of the teeth on each side support the sides of the chain. The spaces between the teeth are extended through the flanges and form internal teeth with which the pawl engages in carrying. The wheels turn on a fixed shaft 17, and pinned to the shaft between the successive wheels is a flanged disk 18 within which the pawl is carried. The flange has an opening to permit the pawl to protrude therethrough while the wheel which carries it is making a tenth of a revolution and passing forward to its zero position. The pawl engages and carries the computing wheel of the next higher computing mechanism. A spring 19, also carried by the wheel of the lower computing mechanism throws the pawl into engagement when it reaches the opening in the flange and a pin 20 carried by the disk is engaged by the tail of the pawl to effect retraction of the pawl. Each chain link is an open frame with a neck and head at one end. The neck is narrower and the head is wider than the opening in the frame but the head is not as long as a diagonal within the frame. The form is such that it can be cut from sheet metal and the ends are bent out of the plane of the body of the link so that the links can be hooked together by bringing them into an angular position with respect to each other and they are locked together when the sides of the links are brought into substantial alignment and so held when connecting the sprocket wheels without excessive slack.

Locators, each of which consists of a bell-crank 21 with a wheel 22 to engage the notches in the flanges and a spring 23 to

press the locating wheel into the flange notch, serve to assure accurate positioning of the mechanisms.

In rapid operation of a machine of this type there is danger of the computing mechanisms through their momentum traveling further than is intended and thereby registering higher than the correct totals. Such overthrow of the particular computing mechanism whose chain is being engaged by the stylus, however, is prevented by the presence of the stylus in the link at the end of the run. But when there is a carry to the next higher computing mechanism its overthrow requires prevention. For this purpose a carry-arresting detent 24 is inserted between each lower computing mechanism and the next higher computing mechanism. These detents are carried by a fixed shaft 25 and each is held frictionally by a spring 26 which lies in a notch in the hub of the detent and bears against the shaft. A lug 27 on the reset wheel of each lower computing mechanism is positioned to engage an arm of the detent and throw the detent in passing to the zero position and carrying the next higher computing mechanism. The detent is thereby engaged with the chain of the next higher computing mechanism after it has been carried one position and the mechanism arrested if by momentum it tends to overthrow to a second position.

A universal bar 28 underlies the links of the computing mechanisms at the ends of the runs so that it will be engaged by the stylus and pushed back at the end of each operation. This bar is carried at the ends of arms 29, 29 which are pivoted to the sides of the frame and for the small arc through which it travels its direction of movement is substantially with that of the upper run of the chains. A second bar 30 between the arms engages and retracts any carry arresting detent which has been thrown into engagement with the chain of a computing mechanism. When a carrying operation takes place at an end movement, since the carry arresting detent is retracted from the next higher computing mechanism while parts are still in motion and it is therefore not effective in preventing overthrow, a series of end movement arresting detents 31, 31 are provided. These are conveniently formed in one piece with a rock shaft 32 and connected through an arm 33 and link 34 with the universal bar. When after drawing the stylus to the end of a run it is withdrawn the universal bar is returned and the end movement arresting detents are retracted by a spring 35.

The mechanisms are reset by turning a crank 36 which is attached to a reset shaft 37 on which the reset wheels turn. The shaft carries a comb 38 with teeth 39, 39 set in a longitudinal groove in the shaft. The

reset wheels carry reset lugs 40, 40 and the comb is normally held by a spring 41 so that the lugs will pass the teeth. By pressing on a button 42 the comb is shifted and the teeth brought into the paths of the lugs. The tooth for engagement with first reset lug normally lies in a mortise 43 and the shaft is locked thereby against rotation. To reset it is therefore necessary first to shift the comb and hold it in shifted position until the revolution of the shaft has commenced. Having passed the mortise the comb is then held in shifted position by reason of this tooth being stopped against the side of the frame until the shaft has been turned sufficiently to reset the mechanisms. This tooth of the comb then reengages the mortise and all the teeth are disengaged from the reset lugs. The mortise is wide enough to permit a slight further movement and carry the teeth past the lugs so that if the crank is turned a second time without intermediate operation of the computing mechanisms there will be no further movement of the reset wheels. Any backward movement so as to return the teeth back in front of the reset lugs when the computing mechanisms are in zero position is prevented by a pawl 44.

Under the table are transverse guides 45, 45 which support a writing tablet 46 which can be drawn out through a slot in one side of the frame and used for noting totals or other purposes. A lug 47 on the underside of the tablet prevents complete withdrawal and removal.

I claim,

1. In an adding machine comprising a series of computing mechanisms of successive denominations each having a computing toothed wheel with shoulders at the bases of the teeth for suitable engagement by the chain, one of the shoulders being undercut to form a flange, the spaces being extended through the flange to form internal teeth in combination with a carrying device between each wheel and the next for engagement with the internal teeth.

2. In an adding machine comprising a series of computing mechanisms of successive denominations and carrying devices connecting each mechanism with the next, the combination of a frictionally held carry arresting detent between each lower computing mechanism and the next higher computing mechanism, and means operated by each lower computing mechanism at the time of carrying to throw the carry arresting detent into engagement with the next higher computing mechanism.

3. In an adding machine comprising a series of computing mechanisms of successive denominations and carrying devices connecting each mechanism with the next, the combination of a carry arresting detent between

- each lower computing mechanism and the next higher computing mechanism, means operated by each lower computing mechanism at the time of carrying to throw the 5 carry arresting detent into engagement with the next higher computing mechanism, and means associated for operation with the end movements of the computing mechanisms to retract the carry arresting detents.
- 10 4. In an adding machine comprising a series of computing mechanisms of successive denominations and carrying devices connecting each mechanism with the next, the combination of a carry arresting detent 15 between each lower computing mechanism and the next higher computing mechanism, end movement arresting detents, means operated by each lower computing mechanism at the time of carrying to throw the carry 20 arresting detent into engagement with the next higher computing mechanism, and means associated for operation with the end movements of the computing mechanisms to retract the carry arresting detents and to 25 engage the end movement arresting detents.
5. In an adding machine comprising a series of computing mechanisms of successive denominations each consisting of a pair of wheels connected by an endless chain and carrying devices connecting each mechanism with the next, the combination of carry arresting detents between each lower computing mechanism and the next higher computing mechanism, and means operated from a 30 wheel of the lower computing mechanism at the time of carrying to throw the carry arresting detent into engagement with the chain of the next higher computing mechanism.
- 35 6. In an adding machine comprising a series of computing mechanisms of successive denominations each consisting of a pair of wheels connected by an endless chain and carrying devices connecting each mechanism with the next, the combination of carry arresting detents between each lower computing mechanism and the next higher computing mechanism, and means operated by each lower computing mechanism at the time of carrying to throw the carry arresting detent into engagement with the next higher computing mechanism, and means for operation with the end movements of the computing mechanisms for retracting the carry arresting detents and engaging the end movement arresting detents.
- 40 7. In an adding machine comprising a series of computing mechanisms of successive denominations each consisting of a pair of wheels connected by an endless chain through which it is operated and carrying devices connecting each mechanism with the next, the combination of carry arresting detents between each lower computing mechanism and the next higher computing mechanism, end movement arresting detents, 45 means operated from a wheel of each lower computing mechanism at the time of carrying to throw the carry arresting detent into engagement with the chain of the next higher computing mechanism, and means for operation with the end movements of the computing mechanisms to retract the carry arresting detents and to engage the end movement arresting detents.
- 50 8. In an adding machine comprising a series of computing mechanisms of successive denominations each consisting of a pair of wheels connected by an endless chain through which it is operated and carrying devices connecting each mechanism with the next, the combination of carry arresting detents between each lower computing mechanism and the next higher computing mechanism, end movement arresting detents, 55 means operated by each lower computing mechanism at the time of carrying to throw the carry arresting detent into engagement with the next higher computing mechanism, and means for operation with the end movements of the computing mechanisms for retracting the carry arresting detents and engaging the end movement arresting detents.

CLIFTON BURT CORELL.
